UNITED STATES PATENT OFFICE.

WILLIAM M. MILROY, OF BALTIMORE, MARYLAND.

HORSE-POWER.

SPECIFICATION forming part of Letters Patent No. 415,215, dated November 19, 1889.

Application filed July 29, 1889. Serial No. 319,055. (No model.)

To all whom it may concern:

Be it known that I, WILLIAM M. MILROY, a citizen of the United States, and a resident of Baltimore, in the State of Maryland, have 5 invented a new and useful Improvement in Horse-Powers, of which the following is a specification.

This invention consists in certain novel combinations of parts, as hereinafter set forth 10 and claimed.

The primary object of the invention is the production of simple and inexpensive horse-power apparatus adapted to be readily attached to and to coact with a fixed upright 15 wooden post, and especially with the king-post of a style of barns common in some sections of the country. The objects of its respective combinations are, first, to provide the master-wheel with a steady frictionless 20 bearing requiring very little lubrication; second, to so construct said bearing as to facilitate assembling the parts or their separation, should occasion arise; third, to guard the spur-gearing against injury to attendants and 25 against accidental obstruction, and, fourth, to facilitate safely attaching a shield to the supporting-post for the purposes last named.

Two sheets of drawings accompany this specification as part thereof.

30 Figure 1 of the drawings is an elevation of a horse-power constructed according to this invention. Fig. 2 is a plan of the parts at and below the section-line 2 2, Fig. 1. Fig. 3 is a sectional perspective view showing details of the shield-attaching devices. Fig. 4 represents a half-plan of the parts at and below the section-line 4 4, Fig. 1. Fig. 5 represents a vertical section of the same portion of the apparatus on the line 5 5, Fig. 4. Fig. 6 35 represents an elevation of the bearing part before the master-wheel is lowered into position thereon; and Figs. 7 and 8 represent inverted plans of the bearing part and of the master-wheel, respectively, illustrating a 40 modification. Figs. 3 to 6, inclusive, are enlarged three diameters from Figs. 1 and 2.

Like letters of reference indicate corresponding parts in the several figures.

In carrying this invention into effect I provide a fixed upright wooden post A with a 45 cast-iron bearing part B, having an angular

bore, and which may be conveniently cast in two or three sizes as to this bore, which is tightly fitted to the post by hewing the sides of the latter, if need be. Said bearing part 55 B is constructed with a lower portion a, conformed to the bore, and provided with screw-holes, through which screws s, Figs. 5 and 6, are driven horizontally into the post, so as to fasten the bearing part securely in its position. A circumferential horizontal track-flange b is next above said portion a, and at top there is a cylindrical portion c. The periphery of the latter is recessed at three or more points, preferably four, for the reception of anti-friction rollers r, which project slightly beyond its circle, and the bearing part is drilled vertically at coincident points for the reception of spindle-rods s², the horizontal upper ends of which carry a second 60 set of rollers r², while their lower ends are screw-threaded and provided with adjusting-nuts n below the flange b. The spindle-rods pass through and pivot said rollers r as well as said rollers r², and ordinarily an occasional 65 lubrication of these rods will suffice for the whole of the bearing part. Notched bolsters b² are formed on the upper end of the bearing part B to coact with said upper ends of the spindle-rods s² in their effective positions, 70 as shown in Figs. 4 and 5. When the nuts n are turned back, the spindle-rods are readily disengaged from the bolsters b², so as to throw their rollers r² within the circle of the bearing portion c, as shown in Fig. 6. 75

With the bearing part made ready, as shown in Fig. 6, a master-wheel C is lowered into position thereon, the bore and upper end of its hub d being adapted to coact with said rollers r and r², respectively, when the latter 80 are turned into position above it and drawn down by the nuts n, which is readily effected. The master-wheel is thus kept in place. The lower end of its hub d is recessed and provided within its recesses with rollers r³, Figs. 95 4 and 5, which coact with the top of the track-flange b. The spindles s³, Fig. 5, of said rollers r³ may be lubricated, should they require it, by applying oil to the sides of the rollers, so as to be carried up to the spindles, 100 or in any approved way.

The bottom of the master-wheel C is pro-

vided with one or more, and preferably two, radial sockets *e* adjoining its hub *d*, and with stirrups *f* in line therewith, the latter provided with horizontal holes at different heights 5 for the reception of the inner ends of draft-levers or sweeps *D* and of pins *p*, whereby the sweeps are removably fastened in place with a convenient provision for raising or lowering their outer ends to suit the horses.

10 Spur-gearing for transmitting motion from the master-wheel *C* preferably comprises internal teeth *t*, formed in the master-wheel at top, so that its rim is smooth, and each tooth may be united with the body of the wheel at 15 end and bottom. The bottoms of the corresponding interdental spaces are beveled, as shown in Fig. 5, so as not to accumulate dust. A spur-wheel *u*, fast on the lower end of a vertical shaft *E*, meshes with said internal 20 teeth of the master-wheel, and the upper end of said shaft is connected by bevel-gears *v w* with a horizontal shaft *F*, which carries a band-pulley *x*, for example, from which power may be readily taken for any purpose 25 for which it may be needed and suited. Such transmitting-shafts *E F* are conveniently supported by strap-bearings *y z*, two patterns of which may suffice, the same to be made of wrought-iron and perforated for 30 screws, which are driven therethrough into the post *A* and an overhead beam *H*, to coincident corners of which the respective bearings are fitted, as indicated in Fig. 4. Brasses *b'* may be embraced by the respective strap-bearings, as indicated in Fig. 4, and supplemental collars *c'*, Fig. 1, may coat therewith 35 as thrust-shoulders where gear-hubs cannot be so utilized.

40 A shield *I*, Figs. 1, 2, and 3, surrounds the post *A* immediately above the master-wheel to mask the main gearing. With peripheral or crown teeth on the master-wheel a shield of greater diameter and with a depending marginal rim would be required. In connection 45 with the internally-toothed master-wheel having a smooth rim, as aforesaid, a superposed shield of no greater diameter than the master-wheel suffices. This shield is conveniently formed in four sheet-metal sections 50 attached to the post by hooks *h* and tie-rods and staples *i i'*, the stems of the hooks *h* and the staples *i'* being driven into the several sides of the post, while the shield-sections have the said rods coupled to them and are 55 provided with holes *h'*, fitted to pivoted heads *h''*, Fig. 3, on the hooks *h*, so that said heads pass through said holes in one position and fasten the shield-sections in place by being turned at right angles, as illustrated by Fig. 60 3. A pair of such hooks to each shield-section keep the same from tilting, and thus keep the joints in the shield sufficiently close, while the shield is very readily attached and removed at will.

65 The whole of the apparatus is designed to be put together and used with the aid of simple instructions by ordinary farm-laborers,

and is especially intended, as aforesaid, for use in barns where a king-post supported at bottom on a flat stone *s'*, Fig. 1, is adapted to 70 serve as the said post *A* and the main cross-beam which rests thereon will serve as the said overhead beam *H*. By propping the latter, removing the stone *s'*, and excavating a very little, if need be, under the king-post, the 75 master-wheel *C* and then the bearing part *B* may be slipped under the post and lifted upward around the same, the former being then propped up until the bearing part is fastened in place, as in Fig. 6. The stone *s'* having 80 been replaced and the props of the overhead beam removed, the weight of the superposed beam and floor, with the load on the latter, keeps the post *A* in its upright position with ample security.

85 For use where it is not convenient or is not considered safe to get beneath the post sectional bearing parts *B* and master-wheels *C* may be constructed as illustrated by Figs. 7 and 8. In each of these figures, *j* represents a diametral joint tightened by screw-bolts in an ordinary way.

90 Details which have not been specified may be of any approved description, and I do not limit my several claims to details which are 95 not stated in them respectively.

Having thus described the said horse-power, I claim as my invention and desire to patent under this specification—

1. In combination with a fixed upright 100 wooden post and the master-wheel of a horse-power surrounding the same and having the bottom of its hub provided with anti-friction rollers, an interposed bearing part having a bore fitted to the post, a perforated lower portion through which screws are driven into the post, and a circumferential track-flange above 105 said perforated portion and provided with anti-friction rollers within and above the hub of the master-wheel, those on the bottom of the latter coating with said track-flange, substantially as hereinbefore specified.

2. In combination with a fixed upright post and a master-wheel surrounding the same, an interposed bearing part made fast on the 115 post and having its upright portion provided with peripheral rollers to coat with the bore of the hub of the master-wheel, rollers at top to coat with the top of the hub, spindle-rods common to both sets of rollers, having horizontal upper ends and screw-threaded lower ends, notched bolsters which engage with said upper ends in their working positions, and screw-nuts on said lower ends of the spindle-rods, substantially as hereinbefore specified. 120

3. In combination with a fixed upright post, a master-wheel, its bearing, and a superposed shield surrounding the post and supported thereby, and spur-gearing for transmitting motion from the master-wheel, said master-wheel being constructed with internal teeth at top as part of said gearing and having a smooth rim, whereby a shield of no greater diameter than the master-wheel suffices to 130
